UNITED STATES PATENT OFFICE

147,504

DESIGN FOR A COMBINED CLOCK AND
PHOTO MOUNT

Stanley F. Miller, Oakland, Calif.

Application December 23, 1946, Serial No. 135,730

Term of patent 14 years

(Cl. D42—7)

To all whom it may concern:

Be it known that I, Stanley F. Miller, a citizen of the United States of America, residing at Oakland, in the county of Alameda and State of California, have invented a new, original, and ornamental Design for a Combined Clock and Photo Mount, of which the following is a specification, reference being had to the accompanying drawing, forming a part thereof wherein:

Figure 1 is a front view of a combined clock and photo mount, showing my new design.

Figure 2 is a top plan view.

Figure 3 is a bottom plan view.

Figure 4 is a view looking at one end,

Figure 5 is a sectional view taken on line 5—5 of Fig. 1, and

Figure 6 is a rear view on a reduced scale.
The photographs shown in Fig. 1 represent no particular individuals.

I claim:

The ornamental design for a combined clock and photo mount, as shown and described.

STANLEY F. MILLER.
